UNITED STATES PATENT OFFICE.

CHARLES LORBER, OF LOUISVILLE, KENTUCKY.

KEY HOLDER.

Application filed May 15, 1926. Serial No. 109,318.

This invention relates to a device for carrying keys and has special reference to a combined key carrier and identification device.

- 5 One important object of the invention is to provide a neat and simple device to which may be attached keys so arranged that they are secured in flat relation on either side of the device.
- 10 A second important object of the invention is to provide a device of this character having straps by means of which the keys carried by the device may be selectively secured to the sides thereof.
- 15 A third important object of the invention is to provide a device of this nature carrying a plurality of key holders or hooks swiveled to one end and shiftable from one side to the other of the device, the invention 20 also being provided with key engaging straps for securing the keys in selected positions.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front view of one form of the invention.

Figure 2 is a plan view of the blank from which the body of this form is constructed.

Figure 3 is a section on the line 3—3 of Figure 1.

Figure 4 is a section on the line 4—4 of Figure 1.

Figure 5 is a front view of a slightly modified form of the device, the modification being in the strap arrangement.

Figure 6 is a section on the line 6—6 of Figure 5.

Figure 7 is a view of another form of the device showing a second modification of the strap arrangement.

Figure 8 is a section on the line 8—8 of Figure 7.

Figure 9 is a face view of a modification of the device made with a single thickness of material.

Figure 10 is an edge view of the form shown in Figure 9.

Figure 11 is a section on the line 11—11 of Figure 9.

Figure 12 is a face view of a modification employing metal clips to secure the key holders or hooks to the body.

Figure 13 is an edge view of Figure 12.

Figure 14 is a greatly enlarged view of the clip used in the form shown in Figure 12.

Figure 15 is a face view of a portion of a device showing a modified form of metal clip.

Figure 16 is a view similar to Figure 14 but showing the modified clip.

In the forms shown in Figures 1 to 8 the body of the device is made from an elongated strip of suitable material such as leather or the like such a strip being shown at 20 in Figure 3. This strip is provided with a pair of slots 21 centrally of its length and is doubled through these slots and stitched as at 22 to form a pocket for the reception of a suitable identification strip or card (not shown). This stitching may be made in any form desired so that the pocket may open either on the side or end. These slots, when the strip is doubled, receive the shanks of key hooks or holders 23 which are swiveled to heads 24 held within the end of the pocket, this arrangement permitting the holders to swing to one side or the other of the body. It is to be noted that any desired forms of hooks or holders may be used and that the heads may also be of any desired form so long as the hooks may swing from one side to the other of the body and swivel to permit free movement of the keys.

In the form shown in Figures 1 to 4 registering slots 25 are provided close to one edge of the body and through these slots passes a strap 26 provided at its ends with snap button parts 27 which cooperate with snap button parts 28 carried on opposite sides of the body 20.

In the form shown in Figures 5 and 6 the same strap and snap button arrangement is used but, instead of the strap running through slots in the body it is doubled around the edge of the body and secured thereto by stitching 29.

In the form shown in Figures 7 and 8 the blank is provided with a pair of elongated U-shaped slits defining the sides and one end of each strap 30, the remaining ends of the straps being left attached to the body.

integrally. In this form the strap from one side of the body is doubled around the edge of the body adjacent the attached end and secured detachably to the opposite side of the body by snap buttons 31.

In the forms shown in Figures 9 to 16 either of the strap arrangements may be used but the body construction is different from that previously described.

10 In Figures 9 to 11 a single thickness of material is used for the body 32, this material being doubled at the top only so that a tubular pocket 33 is provided for the heads of the hooks or holders, the shanks of these members passing through slots 34.

15 In Figures 12 to 14 the hooks or holders are secured to the body 35 by metal clips each having a tubular portion 36 provided with a slot 37. From the tubular portion extends a pair of opposed jaws 37 provided with toothed flanges 38 which are pressed into the material of the body, being there held by the stiffness of the metal.

20 These clips may be modified as in Figures 15 and 16 by dispensing with the toothed flanges and providing holes 39 for rivets 40.

25 In either of these forms the identification may be stamped or embossed on the body as shown at 41 in Figure 9 or may be stamped or embossed on a separate strip 42 of material, which may be metal or other suitable substance, and suitably secured to the body as indicated by stitching 43.

30 It will be obvious that, in any of the forms here shown one or more keys may be secured on one side of the body under the strap on that side while the other key or keys, if any, may be secured in like manner on the other side. Thus any key or keys may be kept separate from the remainder. Also the device may be kept in one's pocket without the keys falling loose and producing undue wear on the pocket.

35 There has thus been provided a simple and efficient device of the kind described and for the purpose specified.

40 It is obvious that minor changes may be made in the form and construction of the invention without departing from the material spirit thereof. It is not, therefore, desired to confine the invention to the exact form herein shown and described, but it is desired to include all such as properly come within the scope claimed.

45 Having thus described the invention, what is claimed as new, is:

1. In a device of the kind described, a body formed of a strip of material, key holding elements pivotally and swivelly connected to one end of the body, a strap carried by the body and free at one end from the body, and means to detachably secure the free end of the strap to the body, said strap being positioned to engage over a key held by one of said elements and resting on

the body, said strip being spaced from the end of the body carrying the key holding elements, whereby the keys held by the strip are exposed to view.

2. In a device of the kind described, a body formed of a strip of material, key holding elements pivotally and swivelly connected to one end of the body, a strap having its central portion secured to the body and its ends lying on opposite sides of the body, and means to detachably connect the ends of the strap to the body, said strap being positioned to engage over a key held by one of said elements and resting on the body.

75 3. In a device of the kind described, a body formed of a strip of material, key holding elements pivotally and swivelly connected to one end of the body, a strap having its central portion secured to the body and its ends lying on opposite sides of the body, and means to detachably connect the ends of the strap to the body, said strap being positioned to engage over a key held by one of said elements and resting on the body, said elements being arranged for positioning on the sides of the body selectively.

80 4. In a device of the kind described, a body formed of a strip of material doubled and stitched to form a pocket to receive an identification card, key holding elements pivotally and swivelly connected to the doubled portion of the body, a strap carried by the body and free at one end from the body, and means to detachably secure the free end of the strap to the body, said strap being positioned to engage over a key held by one of said elements and resting on the body.

85 5. In a device of the kind described, a body formed of a strip of material doubled and stitched to form a pocket to receive an identification card, key holding elements pivotally and swivelly connected to one end of the body, a strap having its central portion secured to the body and its end lying on opposite sides of the body, and means to detachably connect the ends of the strap to the body, said strap being positioned to engage over a key held by one of said elements and resting on the body.

90 6. In a device of the kind described, a body formed of a strip of material doubled and stitched to form a pocket to receive an identification card, key holding elements pivotally and swivelly connected to one end of the body, a strap having its central portion secured to the body and its ends lying on opposite sides of the body, and means to detachably connect the ends of the strap to the body, said strap being positioned to engage over a key held by one of said elements and resting on the body, said elements being arranged for positioning on the sides of the body selectively.

100 7. In a device of the kind described, a body formed of a strip of material and hav-

ing a slot adjacent one edge, key holding elements pivotally and swivelly connected to one end of the body, a strap extending through the slot and having its ends disposed on opposite sides of the body, and means to detachably connect the ends of the strap to the body, said strap being positioned to engage over a key held by one of said elements and resting on the body, said elements being arranged for positioning on the sides of the body selectively.

8. In a device of the kind described, a body formed of a strip of material doubled and stitched to form a pocket to receive an

identification card and having a slot adjacent one edge, key holding elements pivotally and swivelly connected to the doubled portion of the body, a strap extending through the slot and having its ends disposed on opposite sides of the body, and means to detachably connect the ends of the strap to the body, said strap being positioned to engage over a key held by one of said elements and resting on the body, said elements being arranged for positioning on the sides of the body selectively.

In testimony whereof I affix my signature.

CHARLES LORBER.
